Primary Examiner — Catherine Ho(57) **CLAIM**

The ornamental design for an IV ring, as shown and described.

DESCRIPTION

FIG. 1 is a top right perspective view of an IV ring showing my new design;

FIG. 2 is a bottom right perspective view of the present invention thereof;

FIG. 3 is a top left perspective view of the present invention thereof;

FIG. 4 is a bottom left perspective view of the present invention thereof;

FIG. 5 is a front elevational view of the present invention thereof;

FIG. 6 is a rear elevational view of the present invention thereof;

FIG. 7 is a right elevational view of the present invention thereof;

FIG. 8 is a left elevational view of the present invention thereof;

FIG. 9 is a top plan view of the present invention thereof; and,

FIG. 10 is a bottom plan view of the present invention thereof.
